UNITED STATES PATENT OFFICE.

FREDERIC TUDOR, OF BOSTON, MASSACHUSETTS.

CLEAN-OUT FITTING FOR DRAIN-PIPES, TRAPS, &c.

SPECIFICATION forming part of Letters Patent No. 634,850, dated October 3, 1899.

Application filed July 2, 1898. Serial No. 635,025. (No model.)

To all whom it may concern:

Be it known that I, FREDERIC TUDOR, a citizen of the United States of America, and a resident of Boston, county of Suffolk, and State 5 of Massachusetts, have invented certain new and useful Improvements in Clean-Out Fittings for Drain-Pipes, Traps, &c., of which the following is a specification.

The object of the invention and improvements hereinbelow described is the provision of clean-out fittings for drain-pipes, traps, &c., which shall invariably be tight when in use, be readily accessible and removable, and which shall eliminate all danger due to inefficient workmanship. When clean-out fittings as heretofore constructed are first put in place, their security is usually tested by means of a pressure test and the result of defective workmanship corrected in case any fitting betrays a leak. The commonest danger to be apprehended from such contrivances lies in the liability of gaskets and packing to wear out or decay and in imperfect workmanship in repairing and resetting the clean-outs, after which, as a rule, no thorough pressure test is applied, the requirements of local boards of health being usually satisfied by a single test made after the first installation of plumbing. The pressure test is readily applied on new work, but the difficulties and cost of a thorough pressure test prevent its general and repeated use. If the clean-outs as heretofore provided are made tight in the first place, there is no reliable assurance that they 25 will remain so. They are often packed with leather or paper gaskets. The former shrink and the latter decay or break. The clean-outs are the only points of the whole system which are opened to clean out obstructions and accumulations of grease, &c., and when they are replaced it is usually impossible to be sure that the joint is permanently tight, as it is most important that it should be. To remove this great danger to health and to provide clean-out fittings which may be readily accessible and at the same time be rendered perfectly and permanently tight, the invention and improvements herein described will be found adequate and efficient.

50 In the drawings, wherein like letters are uniformly used to designate like parts, Figure

1 is a longitudinal elevation, partly in section, of a clean-out on a straight length of pipe. Fig. 2 is a plan view of Fig. 1 with certain portions hereinafter specified omitted. Fig. 55 3 is a cross-section of Fig. 1, and Fig. 4 a longitudinal section of the clean-out applied to a bend or elbow.

The pipe joint or section A may constitute a portion of the soil-pipe or a part of the connection of a trap. This pipe-fitting is provided with a lateral opening, of which the edge e is properly shaped to constitute a seat for the cover E.

I use the term "seat" in a general sense. 65 It may be a bevel-edged surface, as in Figs. 1 and 3, or a screw-thread, as in Fig. 4.

Upon the pipe-fitting A, preferably cast as an integral portion thereof, is a wall B, which surrounds the seat e of the cover E (which 70 is proportioned and shaped so as to fit the seat e closely, as in Fig. 1, or when a circular cap or cover is employed is screwed into a corresponding circular seat, as in Fig. 4) and is provided with a projection D, which is of 75 service when the cover E is to be removed or put in place. The wall B forms a receptacle around and over the cover-seat e. In the form shown in Figs. 1 to 3, inclusive, the cover is held in place by yokes G and plates F, 80 through which the ends of the yoke pass and which may be drawn tightly into place by means of nuts g, which screw on over the ends of the yoke G. In Fig. 2 these yokes are not shown. In the form shown in Fig. 4 85 this mode of securement is discarded and a screw-thread at e supplied instead. The projection D in this case may be squared, so as to form a convenient hold for a key with which the cover may be tightly screwed in 90 place. When the cover is in place, the workman fills the receptacle formed by the retaining-wall B with a plastic cement which hardens after a short interval. Plaster-of-paris is a cement which may be readily prepared 95 and applied.

A gasket on the seat e may be used, but the cement renders this unnecessary in most cases.

In order to economize in cement used, the 100 receptacle within the retaining-wall B may be contracted by forming the cover E with

the flange C at or near the outer edge of the cover. A rim of cement will thus be formed between the wall B and flange C.

In Fig. 4 I have shown the cement II on one side filling the entire receptacle between the retaining-wall B and the projection D and on the other side at h confined to the contracted space between the retaining-wall B and flange C.

10 For further security the retaining-wall B may be formed with an inwardly-projecting lip b. This lip constitutes a choking-flange which effectually resists any ordinary effort to remove or displace the cover E when the 15 plaster or cement has hardened. Any obstruction may be employed to perform this function, the idea being to offer an effective obstacle to the removal of the cement, which thus forms a key or plug, as well as a seal.

20 When it is desired to remove the cover, the cement II can be readily broken out and the cover lifted from its seat. When the cover is replaced and the plaster or cement is mixed 25 and the receptacle therefor filled, there can be no fear of a leak from the joint e. Only the most ordinary skill is required to mix and apply the cement, so that the danger heretofore to be apprehended from unskillful workmanship is removed. I have contrived the 30 cover E so that it offers no obstruction and forms no inner receptacle whereby the drain or trap may be clogged. Ordinarily the clean-outs on the side of drain-pipes are attached to a chamber on the side of the pipe, sometimes 35 in the form of a T and sometimes rectangular or box shaped. Such chambers form lateral receptacles in which any slight substance is liable to lodge and by its lodgment form an obstruction to impede the passage of 40 other matter or detain it, thus increasing the stricture within the pipe.

The cover E is constructed with its inner face shaped to conform to the general shape of the pipe-fitting to which it is applied.

45 If the pipe is cylindrical, as in Fig. 1, the cover E is convex on the under side, with a cylindrical surface of the same radius as the inner radius of the pipe. If the pipe-fitting to

which the cover is applied is of another shape—say a quarter-turn, as in Fig. 4—the 50 inner surface of the cover is shaped so that when the cover is in place the pipe-fitting and cover form a substantially smooth and unbroken inner surface.

In Fig. 4 the cover E has its inner surface 55 shaped to coincide with a torus having radii of curvature the same as those of the pipe-fitting itself.

In a fitting such as shown in Fig. 4 marks or notches on the outside of the pipe-casing 60 and cover should be provided, so that when these coincide or assume a predetermined relationship or position the workman may know that the inner surface of the pipe and cover are also coincident. With clean-out 65 covers provided with the cement seal herein described the apertures may be placed on the under side of a pipe or trap with the same security as when they are placed on the top.

What I claim, and desire to secure by Letters Patent, is—

1. In a clean-out fitting, a cover, its seat, a receptacle over the seat-joint, and a filling of cement in the said receptacle, substantially as described.

2. A pipe-fitting provided with a clean-out aperture, a retaining-wall around the aperture, a cover fitting said aperture and a filling of cement within the retaining-wall and covering the seat-joint, substantially as described.

3. A pipe-fitting provided with a clean-out aperture, a retaining-wall surrounding said aperture, a cover fitting the aperture, a filling of cement within the retaining-wall and covering the seat-joint, the said retaining-wall provided on the inside with a choking-flange, whereby the cement is secured against dislodgment, substantially as described.

Signed by me at Boston, Massachusetts, this 90 30th day of June, 1898.

FREDERIC TUDOR.
